UNITED STATES PATENT OFFICE.

WILLIAM D. CHAPIN, OF WAKEFIELD, NEW YORK, ASSIGNOR TO HIMSELF,
AND J. HULL BROWNING, OF TENAFLY, NEW JERSEY.

DESIGN FOR A LINK FOR BELT-FASTENERS.

SPECIFICATION forming part of Design No. 28,062, dated December 21, 1897.

Application filed September 16, 1897. Serial No. 651,953. Term of patent 7 years.

To all whom it may concern:

Be it known that I, WILLIAM D. CHAPIN, a citizen of the United States, residing in Wakefield, in the county of Westchester and State of New York, have invented and produced a certain new and original Design for Links for Belt-Fasteners, of which the following is a specification, reference being had to the accompanying drawings, forming a part thereof.

10 Figure 1 is a side or face view of the link, and Fig. 2 is a corresponding edge view.

The leading features of my design are the centrally-perforated lobes or swells connected by a portion curved out of the line of the lobes and a point projecting from the inner face of the curved portion toward said line.

15 The lobes are marked A A. The outline of each is circular, as at A', and each is provided with an orifice a, produced in its center.

20 B is a portion curving in an arch form from one lobe to the other. The upper curve B'

flows smoothly into the circular lines A', and the lower curve B², struck from a less-distant center, joins the lines A' by curves B³ of short radius. All portions are of the same thickness and lie in the same plane. 25

C is a point projecting downwardly from the under side of the curve B², lying midway between the lobes A A and extending nearly but not quite to a line passing through the 30 centers of the orifices a a.

I claim—

The design for a link for belt-fasteners herein shown and described.

In testimony that I claim the invention 35 above set forth I affix my signature in presence of two witnesses.

WM. D. CHAPIN.

Witnesses:

CHARLES R. SEARLE,
R. W. ROSANDER.
